UNITED STATES PATENT OFFICE.

RAYMOND E. ACKLEY, OF CHICAGO, ILLINOIS, ASSIGNOR TO R. R. DONNELLEY AND SONS COMPANY, OF CHICAGO, ILLINOIS, A CORPORATION OF ILLINOIS.

BOOK BINDING AND COVERING MACHINE.

Application filed March 21, 1927. Serial No. 177,139.

This invention relates to an improvement in bookbinding and covering machines.

An object of this invention is to provide a suitable means for scoring the back of the book transversely so as to enable it to receive and hold the glue or a suitable adhesive which is applied thereto. Various means have been suggested and tried for this purpose, but for one reason or another, 10 each has been more or less unsatisfactory.

This and other objects have been accomplished by the present invention which consists essentially in a spiral cutter which is driven in timed relation to the speed of the 15 chain carrying the books through the machine so that when once the teeth of the cutter engage the back of the book they move forward at the same speed as the books themselves.

20 This invention is an improvement of the book binding and covering machine shown and described in the patent to Bredenberg No. 1,073,324, granted September 16, 1913, and adapted to be used in conjunction therewith.

The invention is fully described in the following specification and shown in the accompanying drawings, in which:

Figure 1 is a partial side elevation of the 30 Bredenberg book binding and covering machine showing the cutter applied thereto;

Fig. 2 is a top plan view of the same;

Fig. 3 is an end elevation of the same;

Fig. 4 is an enlarged end view of the cutter partly in section;

Fig. 5 is a combined longitudinal section and side elevation of the same;

Fig. 6 is a partial enlarged detail of the longitudinal bar for supporting the cutter;

Fig. 7 is a partial perspective of a book showing the transverse cutters therein;

Fig. 8 is a top plan view of a modified form of rotary cutter; and

Fig. 9 is a side elevation of the same.

The embodiment illustrated is a book binding and covering machine having a main frame 10 to which is attached, by means not shown, two parallel channels 11 and 12 having facing guide ways adapted 45 to receive rollers 13 and 14 which are journaled on suitable pins which serve to connect the links 15, 16, etc., of a continuous chain. The mechanism for driving this

chain is fully illustrated and described in the patent to Bredenberg mentioned above. 55

These links carry plates 17 which are movably secured to the links 15, 16 by means of pins 18 which pass through bosses 20 on the chain and are pressed toward the links by means of springs 21 on the pins 18. 60 Mechanism not shown herein, but fully shown and described in the patent to Bredenberg, presses the pins 18 outwardly against the action of the compression springs 21 so that the signatures necessary to make 65 one book may be dropped into the space between the link 15 and the plate 17, after which the pins 18 are released and the spring 21 forces the plate 17 in until it grips the unbound book A. During this time, however, care is taken that the bottoms of these signatures lie uniformly in a horizontal plane. 70

The binding of these signatures into a book is accomplished by cutting off the 75 folded backs as by a knife or by the rotary cutter 36 of the Bredenberg patent, leaving the book a bundle of separate sheets. These are secured together by gluing the whole 80 much as in making a glued tablet. As the strength of the book depends upon the bond between glue and leaves, book manufacturers have sometimes tried cutting notches across the backs to strengthen this bond. After gluing the cover (not shown) is folded 85 about the whole and pressed in place, the glue serving to hold all these sheets and cover together.

Various schemes and means have been devised for cutting or scoring the backs of 90 these signatures and the present invention employs a simple and effective means for accomplishing this purpose and which at the same time scores all the pages to a uniform depth, the scoring at the same time 95 lying substantially directly across the back of the book.

This scoring mechanism consists essentially of a spiral cutter B which is mounted upon a shaft 22, the latter being journaled 100 in suitable bearings 23, 24 which in turn are carried upon a rocker-shaft 25 which is journaled in bearings 26 which are adjustably mounted on brackets 27 by means of bolts passing through parallel slots 28 therein. 105 These brackets 27 are journaled upon a shaft

29 which is carried by a member 30, which is secured to the main frame 10.

A lever arm 31 is secured to the shaft 25 and has an adjusting screw 32 fastened to one end of the main frame so that by raising and lowering the end of the lever arm 31, the spiral cutter B may be moved away from and toward the unbound book A which is to be scored.

10 The rotary cutter is driven from the main shaft 33 by means of the gear train 34, 35, the sprockets 36, 37, 38 and 39. Thus it will be seen that these gears and sprockets increase in speed continuously so that the 15 rotative speed of the shaft 22 is much greater than that of the main shaft 33, because of this increase in speed it is difficult to start the book making machine with this gear attached. I have accordingly provided the 20 shaft 22 with a pulley 40 which is driven by means of a friction belt 41 from a motor 42. Thus the motor 42, which is started at the same time as the book binding machine, starts the relatively high speed shaft 22 and 25 thus relieves the main shaft 33 of the load of bringing these high speed shafts up to their normal speed.

The rotary cutter B is provided with a toothed helical blade or rather a series of 30 blades 43 which will later be described in detail. The pitch of these blades is such and the shaft 22 is so geared to the mechanism which drives the chain 15, that the spiral blades advance at the same rate as the 35 books A.

It will now be observed that the axis of the shaft 22 is set at a slight angle to the path of the books A, this angle being substantially the angle made by the spiral 40 blades so that the books cross these blades substantially at right angles to the blades at the points of contact. In this way the 45 grooves C in the back of the book A (Fig. 7) extend at right angles across the back.

45 It will be obvious that the book A as it approaches the spiral cutter B is well to one side of the axis of the cutter and that as it advances it crosses the axis of the cutter. Thus, where the book A is of a considerable 50 thickness, the cutter teeth will first engage only the nearest leaves of the book, but as it advances more and more of the leaves will be brought into contact with the spiral blades 43 with the result that when the book is 55 driven all the way across, the grooves C will be found to be cut to a uniform depth throughout. The depth of this cut is regulated by means of the adjusting screw 32.

The rotary cutter B is preferably made up 60 of end plates 44 mounted upon a tube 45 and having a series of notches 46 (Fig. 4) which are adapted to receive the notched ends 47 of the parallel bars 48. These bars in turn are provided with notches 49 ar- 65 ranged therein in spiral form so as to re-

ceive the toothed helical blades 43. These blades are preferably stamped from sheet steel or the like which is then hardened and tempered. These blades are annular in form and are severed at 43^a (Fig. 4) and are sprung so that the end of one blade is secured in alignment with the end of the next blade by means of plates 50 or the like which are secured in place by means of bolts or rivets 51.

75 The bars 48 are provided with tapped holes 52 which are adapted to receive adjusting screws 53. After adjustment, the bars are securely locked by means of set-screws 54.

80 This rotary cutter may be made in the form of a single pitch thread or it may be made double or triple pitch if so desired.

In Figs. 8 and 9 is shown a modified form 85 of rotary cutter in which the cutter or saw 55 is wound spirally and secured in a plate 56 which is carried by a shaft 57 which is journaled in a bracket 58. A bevel gear 59 is keyed on the shaft 57 and meshes with a gear 60 keyed on a shaft 61 which is suitably journaled in a bracket 62. The brackets 58 and 62 being carried by the main frame, the shaft 61 is driven by a sprocket 63 and chain 64 in tuned relation to the speed of the chain 15 in the same way as the shaft 22 so that the books A will move forward at the same rate as the cutter blade 55. In this way, the cutter blade cuts a succession of notches in the back of the book as shown in Fig. 7.

85 Thus it will be seen that a very simple 90 form of cutter is provided which has no reciprocating parts and which will automatically keep in step with the advancing book since it is positively geared to the mechanism which drives the chain 15.

95 After the book passes the cutter, glue is spread upon the back by mechanism similar to that shown in the previously mentioned patent to Bredenberg after which a cover is secured thereon in a well known manner.

100 While I have shown and described but a single embodiment of this invention, it is to be understood that it is capable of many modifications. Changes therefore in the construction and arrangement may be made 105 which do not depart from the spirit and scope of the invention as disclosed in the appended claims.

I claim:

1. In a book binding machine, a continuous traveling belt having means to grip unbound books at intervals and hold them with their back edges in alignment, and transverse cutting means traveling at the same speed as the book for cutting a series 115 of notches in the back edges of said book as it advances.

120 2. In a book binding machine, a continuous traveling belt having means to grip unbound books at intervals and hold them 125

with their back edges in alignment, and transverse rotary cutting means traveling at the same speed as the book for cutting a series of notches in the back edges of said book as it advances.

3. In a book binding machine, a continuous traveling belt having means to grip unbound books at intervals and hold them with their back edges in alignment, and transverse cutting means traveling continuously at the same speed as the book for cutting a series of notches in the back edges of said book as it advances.

4. In a book binding machine, a continuous traveling belt having means to grip unbound books at intervals and hold them with their back edges in alignment, and a rotating member having a helical cutter adapted to rotate about an axis at an angle to the direction of travel of said books.

5. In a book binding machine, a continuous traveling belt having means to grip unbound books at intervals and hold them with their back edges in alignment, and a rotating member having a rotary cutter adapted to rotate about an axis at an angle to the direction of travel of said books, the pitch and speed of said cutter being such as to cause it to travel at the speed of said books, said cutter lying substantially at right angles to the length of said book at the points of contact of the cutter and book.

6. In a book binding machine, a continuous traveling belt having means to grip unbound books at intervals and hold them with their back edges in alignment, a rotating member having a rotary cutter adapted to rotate about an axis at an angle to the direction of travel of said books, means for positively driving said cutter in timed relation to the speed of the books, and friction means for assisting in driving said cutter.

7. In a book binding machine, a continuous traveling belt having means to grip unbound books at intervals and hold them with their back edges in alignment, and a rotating member having a rotary cutter adapted to rotate about an axis at an angle to the direction of travel of said books, said books traveling endwise along a line substantially at right angles to the cutters at the points of contact.

8. In a book binding machine, a continuous traveling belt having means to grip unbound books at intervals and hold them

with their back edges in alignment, a shaft adjacent said belt and driven in timed relation thereto, said shaft carrying a rotary cutter, the plane of the books cutting the axis of the cutter substantially at right angles to the plane of the cutter at the point of contact.

9. In book binding machine, a continuous traveling belt having means to grip unbound books at intervals and hold them with their back edges in alignment, and a shaft adjacent said belt and beneath the same and driven in timed relation thereto, said shaft carrying a rotary cutter, the plane of the books cutting the axis of the cutter substantially at right angles to the plane of the cutter at the point of contact.

10. In a book binding machine, a continuous traveling belt having means to grip unbound books at intervals and hold them with their back edges in alignment, and a shaft adjacent said belt and driven in timed relation thereto, said shaft carrying a rotary cutter having a plurality of turns, the plane of the books cutting the axis of the cutter substantially at right angles to the plane of the cutter at the point of contact.

11. In a book binding machine, a continuous traveling belt having means to grip unbound books at intervals and hold them with their back edges in alignment, a rotating member having a rotary cutter adapted to rotate about an axis at an angle to the direction of travel of said books, said rotary member being hingedly carried by the frame of the machine, and means for adjustably swinging said member about the hinge to adjust said member with respect to the book.

12. A rotary cutter of the class described comprising a frame, a series of parallel bars carried thereby having spaced notches therein, and a plurality of annular helically arranged cutter elements carried in said notches.

13. A rotary cutter of the class described comprising a frame, a series of parallel bars carried thereby having spaced notches therein, and a plurality of annular spirally arranged cutter elements carried in said notches, the adjacent ends of said elements being secured together to form a continuous helix.

In witness whereof, I have hereunto set my hand this 23rd day of February, 1927.

RAYMOND E. ACKLEY:
